EDGAR B. HYATT, OF PORTLAND, OREGON.

GARAGE-DOOR CONTROL.

1,410,314.

Specification of Letters Patent. Patented Mar. 21, 1922.

Application filed November 4, 1920. Serial No. 421,619.

To all whom it may concern:

Be it hereby known that I, EDGAR B. HYATT, a citizen of the United States, and resident of Portland, in the county of Multnomah and State of Oregon, have invented a new and useful Garage-Door Control, of which the following is a specification.

This invention relates more particularly to garage doors.

10 The object of my invention is to provide an exceedingly simple means for operating garage doors from an automobile.

I attain this result in the manner described in the following specification and illustrated in the accompanying drawing, in which:

Figure 1 is a plan of a garage. Figure 2 is a sectional elevation. Figure 3 is an enlarged detail of a crosshead for operating the doors along the line 3—3 in Figure 2. Figure 4 is a side elevation of Figure 3 along the line 4—4 in Figure 1.

Similar numbers of reference refer to the same or similar parts throughout the 25 several views.

Referring in detail to the drawing, I have illustrated in outline the walls 5, the floor 6, the ceiling 7, and the doors 8 of the usual garage. To each of these doors I have 30 hinged a connecting rod 9 by means of the bracket 10. The two rods 9 are joined together by means of a bolt 10^a which threads into a crosshead 11 which slides on the fixed shaft 12 on which it is prevented from rotating by the pin 13 which moves freely in a splineway in the shaft 12. The shaft 12 is supported at either end in the brackets 14.

On the lower side of the crosshead 11 is 40 hinged a connecting rod 15 by means of the shouldered screw 16 which is prevented from turning by means of the cotter 17 passing through the crosshead 11.

The further end of the connecting rod 15 is attached to an adjustable crank-arm 18 45 which is secured to a worm wheel 19 mounted in the frame 20 and driven by the worm 21 on the shaft 22, which is rotated by the grooved pulley 23, which, in turn, is driven through a round belt 24 from the 50 pulley 25 on the motor 26.

Projecting laterally from the crosshead 11 is an arm 27 whose enlarged end 28 is tapped for the rods 29 and 30, both of which have bent ends 31 whose own weight always 55 holds them in the downward position, which can be further insured by placing a lock nut

on the threaded portions of the rods and jamming same against the member 28 when the rods 29 and 30 are properly adjusted. The downturned ends 31 act as trips for 60 engaging the arm 32 of the toggle switch 33, one of the members 31 throwing the switch in one direction and the other throwing it in the opposite direction. The switch 33 is placed in the motor circuit 34 which 65 is also controlled by a switch 35, which is placed out on the driveway at a point accessible from the driver's seat when the car is stopped sufficiently far from the garage to permit the opening of the doors. 70

It is evident that by the use of a connection to the lighting circuit that switch 35 may also control the light within the garage, without departing from the spirit of my invention. 75

While I am aware that other devices have been constructed for this purpose employing reversible motors, etc., with their attendant complications, I have chosen to use the ordinary crank motion as the simplest 80 form for my device, permitting thereby the use of a one-way motor and providing a maximum leverage for the operating parts when starting to close or stopping the motion of the doors when closed. By setting 85 the tripping mechanism so that the door will close with the crank arm 18 on a dead center it would be impossible to open the garage doors regardless of the pitch of the worm 21.

When desiring to use this device on 90 garages having double doors it is only necessary to place an evener across the two crossheads 11 and attaching this evener to the connecting rod 15, all of which could be done without departing from the spirit of 95 my invention.

The operation of my device is as follows: When desiring to enter the garage it is only necessary to operate the switch 35, which is a three-way switch wired as indicated. 100 This action closes the motor circuit which causes the crank arm 18 to rotate and moves the crosshead 11 toward the front of the garage, thereby forcing the doors 8 outwardly until a point is reached where the 105 member 31 engages the lever 32 and automatically stops the motor.

It will be observed that the toggle switch is necessarily a three-way switch in order that the motor can again be started after 110 it has been stopped by means of the trips 31. The operation of the switch 35 will then

continue the rotation of the motor and the completion of the cycle by the crank arm 18 which will restore the doors 8 to their former closed position.

5 While I have thus illustrated and described my invention it is not my desire to limit myself to this precise form or method of application, but intend that it shall cover all forms and modifications that fall fairly 10 within the appended claims.

What I claim as new and desire to protect by Letters Patent of the United States is:

15 1. A garage door consisting of a pair of swinging doors, in combination with a fixed horizontal rod mounted at right angles to the meeting point of the doors near their top, a crosshead on said rod, two connecting rods branching out from said cross-head and attached to the swinging ends of

the doors, a one-way motor, a crank driven by said motor whose axis is at right angles to and in the same vertical plane with said fixed rod, a connecting rod joining said crank to said crosshead, adjustable pendant 25 stops on said crosshead, a three-way toggle switch whose lever is moved between said stops, and a three-way button switch wired with said toggle switch to control said motor from said crosshead or by hand. 30

2. In a door closing device, the combination of a motor driven door actuating mechanism having a crosshead member provided with a lateral projecting standard through which are threaded from opposite sides a 35 pair of down-turned trip members, and a fixed toggle switch in the circuit of said motor having its operating lever between said down-turned trip members.

EDGAR B. HYATT.
